CLAIM

The ornamental design for a monitor support bracket as shown and described.

DESCRIPTION

FIG. 1 is a front, top and left side perspective view of a monitor support bracket showing my new design; FIG. 2 is a front elevational view thereof; FIG. 3 is a rear elevational view thereof; FIG. 4 is a top plan view thereof; FIG. 5 is a bottom plan view thereof; FIG. 6 is a left side elevational view thereof, the right side being a mirror image thereof; and, FIG. 7 is a front, top and right side perspective view thereof, shown in an environment of use. The broken lines shown in FIGS. 1-6 illustrate portions of the monitor support bracket that form no part of the claimed design. The broken lines illustrating the monitor, arm and clamp in FIG. 7 are environment, while the remaining broken lines in FIG. 7 illustrate portions of the monitor support bracket that form no part of the claimed design.

1 Claim, 7 Drawing Sheets
